ton, Del., a corporation of Delaware

Application February 15, 1946, Serial No. 647,786

4 Claims. (Cl. 121—41)

1

This invention relates to hydraulic machinery, and, in particular, to control mechanism for hydraulic pumps of the variable delivery type.

Pumps of this type which may be of various constructions, for instance of the construction shown in U. S. Patent No. 2,250,705 to Walter Ernst, are provided with a control member movable into various positions for varying the delivery of the pump. Such a control member has generally associated therewith a control mechanism which in response to a predetermined pressure in the hydraulic system, of which the pump forms a part, will automatically shift the control member into a position for causing the pump approximately to stop delivery of fluid.

These pumps have been quite satisfactory in ordinary hydraulic circuits. However, where it is desired, as for instance in hydraulic circuits for drawing presses, to maintain a certain dwell, i. e., to hold the drawing pressure for a certain period of time, the control mechanism for variable delivery pumps as heretofore known have not been able to meet the necessary requirements. The reason for this failure consists in that the hydraulically operated control mechanism did not stop the control rod in the position in which the pump does not deliver any fluid or only so much as it is necessary to make up for leakage. Instead, the control rod moved beyond this position, and as a result thereof, fluid was transferred from one side of the control member to the other side thereof and back so that a fluctuation of the control rod back and forth took place in order to sense the correct neutral position.

It is, therefore, an object of the invention to provide a control mechanism for use in connection with variable delivery pumps which will overcome the above mentioned drawback.

It is another object to provide a control mechanism for variable delivery pumps which can easily be adjusted so as to definitely limit the stroke of the control rod when the latter shifts the pump into substantially no delivery position for holding a predetermined pressure.

It is a further object of the invention to provide a variable delivery pump with a control mechanism which will automatically reduce the delivery of the pump to substantially zero in response to a predetermined pressure at the delivery side of the pump, while preventing any fluctuation of the control member of the pump.

It is also an object of the invention to provide a control mechanism of the above mentioned type which will be simple in construction and will

2

easily be adjustable to vary the pressure for actuation of the control member.

These and other objects and advantages of the invention will appear more clearly from the following specification in connection with the accompanying drawing in which:

Figure 1 is a section through the control mechanism according to the invention.

Figure 2 illustrates a hydraulic circuit comprising a variable delivery pump with the control mechanism illustrated in Figure 1.

General arrangement

In general, the arrangement according to the present invention comprises a casing housing a spring which engages a part of a valve member adapted to control the delivery of pilot fluid to the servomotor for the variable delivery pump. The casing housing this spring comprises an abutment which will be engaged by the valve member and will stop the movement of the latter when the valve member is actuated in response to a predetermined pressure governing the movement of the pump to substantially no delivery position. To vary the pressure at which this shifting movement of the pump is to be effected, the casing housing the spring is provided with adjusting means for adjusting the tension of the spring.

Structural arrangement

Referring now to the drawing and Figure 1 thereof in particular, this figure shows a part of the pump casing 10 of a variable delivery pump. Connected to the pump casing 10 is a cylinder 11 having a bore 12 and a larger bore 13 in which a piston 14 is reciprocably mounted. The piston 14 has a radial bore 15 and a horizontal bore 16 which latter is adapted to effect communication between the recess 17 in the larger portion 14a of the piston and the annular recess 18 in the smaller portion 14b of the piston 14. The radial bore 15 communicates with an annular recess 19 in the piston portion 14b. The piston 14 has connected thereto a sleeve 20 provided with radial bores 21 and 22 respectively in alignment with the bore 15 and the annular recess 18. The piston 14 is adapted to be engaged by a split ring 23 which in its turn engages an annular groove 24 of the servomotor rod 25. The servomotor rod 25 has radial bores 26 adapted to effect communication between the cylinder bore 12 and the bore 27 in the servomotor rod 25.

Slidably mounted in the bore 27 is the plunger

head 28 of a plunger 29. The plunger 29 has a second plunger head 30 having the same diameter as the plunger head 28 and being slidably mounted in the bore 32 of the sleeve 20. The plunger 29 is furthermore provided with a flange 33 adapted to enter the recess 17 in the larger portion 14a of the piston 14. The plunger 29 then extends through packing 34 located in the lid 35a which latter is connected to the cylinder 11 in any convenient manner. The left end of the plunger 29 with regard to Figure 1 extends into a cylinder 35 having a bore 36 and a larger bore 37. Reciprocably mounted in the bore 37 is a piston 38 which is clamped against the step 39 of the plunger 29 by means of a nut 40 which latter is screwed upon the end of the plunger 29 and secured thereto by a threaded pin 41.

The nut 40 is engaged by one end of a spring 42, the other end of which abuts a disc 43 movable in the bore 45 of the casing 46. The casing 46 is screwed into the cylinder 35 and is held in position with regard thereto by a locking nut 47. The disc 43 is adjustably engaged by an adjusting screw 48 which latter is covered against outside interference by an acorn nut 49. The device is furthermore provided with seals 50, 51 and 52 to prevent leakage. Furthermore, the plunger 29 has a longitudinal bore 53 therein which communicates with radial bores 54 and 55 for conducting drainage.

Linked to the cylinder 35 is a link 56 which in its turn is connected to the lid 35a by a link 57.

The device shown in Figure 1 may be arranged in a hydraulic circuit such as the circuit shown in Figure 2. This circuit shows one side of the pump 10 connected to a conduit 58 which in its turn is connected with the conduit 59. One end of the conduit 59 leads to one side of a hydraulic motor 60 which may be of any desired type or may also constitute a press. The other side of the motor 60 is connected with a conduit 61 leading to the pump 10. The pump 10 is provided with centering springs 62 and 63 adapted to actuate the shift ring or flow control member 64 by means of the centering rod 65, for shifting the pump 10 into neutral or no delivery position in case of a failure of power to thereby prevent accidents. This centering arrangement does not form a part of the present invention and is more fully described in U. S. Patent No. 2,184,665 to Walter Ernst. Also connected to the shift ring 64 is the servomotor rod 25.

The cylinder bore 12 in the cylinder 11 is connected by means of a bore 66 with a conduit 67 leading to a fluid reservoir or tank 68. Also connected to the tank 68 is a conduit 69 leading to the suction side of a pilot pump 70 which may be of any desired type. The pressure side of the pump 70 communicates through a conduit 71 with a bore 72 in the cylinder 11. Interposed between the suction and pressure side of the pump 70 and communicating with the conduits 69 and 71 is the pressure relief valve 73 of any standard construction. The conduit 59 further communicates through a flexible conduit 74 with the bore 75 leading into the bore 37.

Operation

It may be assumed that all parts of the hydraulic circuit shown in Figure 2 occupy the position shown in the drawing. If it is now desired to actuate the motor 60, so as to move the latter in forward direction, the lever 56 is

shifted to the left with regard to the drawings. As a result thereof the cylinder 35, together with the casing 46 and the plunger 29 as a unit move toward the right. Consequently, fluid connection is now stopped between the conduit 71, a bore 15 and 21 and recess 17. Therefore, provided that the pilot pump 70 has been started, pressure fluid will be supplied by the pilot pump 70 to the left hand side of the piston area 14a 10 of the piston 14. As a result thereof, the piston 14 will move toward the right and, will shift the servomotor rod 25 accordingly so as to place the pump 10 on forward stroke. The pump 10 will then deliver pressure fluid through conduit 59 to the hydraulic motor 60, while the exhaust from the motor 60 will be returned through conduit 61 to the pump 10.

When during the operation of the motor 60 a predetermined pressure for which the spring 42 has been set has been built up in the motor 60, this pressure will be conveyed through conduits 59 and 74 to the bore 37 where it will act on both the step 39 and the piston 38. Inasmuch as the area of the piston 38 is the larger one, the pressure acting thereupon will move the piston 38 and through nut 40 also the plunger 29 toward the right until the nut 40 abuts the adjacent end of the casing 46. When this position has been reached, pressure fluid from the pump 70 will be conveyed through conduit 71 and bore 15 to the right side of the piston portion 14a while fluid connection is interrupted between the conduit 71 and the left side area of the piston portion 14a. Consequently, the pressure fluid acting on the right hand side of the piston portion 14a will move the piston 14 leftwardly until the relative position between the piston 14 and the plunger 29 is that shown in Figure 1. During this leftward movement of the piston portion 14a the fluid 40 expelled from the recess 17 will pass through bore 16, annular recess 18 and bore 32 as well as the radial bores 26 into the exhaust conduit 67 from where it will be returned to the fluid reservoir or tank 68. During this leftward movement of the piston 14, the servomotor rod 25 will likewise be moved leftwardly in such a manner that when piston 14 comes to rest the shift ring of the pump 10, and consequently also the pump 10, is in substantially no delivery position. Since the plunger 29 is definitely arrested due to the abutment of the nut 40 against the casing 46, no hunting of the plunger 29 can take place, and the pump 10 will stay in neutral position, thereby maintaining its pressure holding position constant until by movement of the lever 56 it is desired to place the pump 10 in the reverse stroke.

To this end the lever 56 is shifted to the right with regard to Figure 1, thereby also shifting the plunger 29 toward the right. This will again space the nut 40 from the casing 46, while simultaneously establishing again fluid connection between conduit 71 and the right hand area of the piston portion 14a. Consequently, pressure fluid from the pilot pump 70 will cause the piston 14 to move further leftwardly, thereby placing the pump 10 on return stroke. Pressure fluid from the pump 10 will then be conveyed through conduit 61 to motor 60 and operate the same in the reverse direction. The pump 10 may be stopped at any time during the operation of the motor 60 by shifting the lever 56 leftwardly with regard to Figure 1 so that pressure fluid will be conveyed from conduit 71 to the leftward area of the piston portion 14a. The fluid pressure will 75 then move the piston 14 toward the right until a

relative position has been obtained as shown in Figure 1. In this position, the piston 14 comes to a stop while the pump 10 is in substantially no delay position.

It may be noted that the plunger portions 28 and 30 have the same diameter so that they are hydraulically balanced and that no drainage which may enter the space between the said two plunger portions will in any way affect the position of the plunger 29.

If it is desired to vary the pressure at which the pump 10 should move into substantially no delivery position, it is merely necessary to unscrew the acorn nut 49 and adjust the adjusting screw 48 to the desired extent.

It will be understood that the present invention is by no means limited to the particular construction shown in the drawing but comprises any modifications within the scope of the appended claims.

Having thus fully described my invention, what I claim as new and desire to secure by Letters Patent, is:

1. In a servomotor, a casing, a double acting ram in said casing, a valve in said ram for controlling the supply of fluid to and from opposite ends of said casing, a rod on said valve having a piston, a cylinder on said rod surrounding said piston, resilient means in said cylinder urging said piston toward one end thereof, means to admit pressure to said one end of said cylinder to urge said piston toward the other end thereof, and mechanism linked to said cylinder for normally actuating said cylinder, rod and valve as a unit and for holding said cylinder stationary when said piston is actuated by pressure whereby said valve may be shifted independently of said mechanism and cylinder.

2. In a servomotor, a reciprocable ram, a valve for controlling the supply of fluid to and from opposite ends of said ram, a projection on said valve having a piston, cylinder means receiving said piston, resilient means in said cylinder urging said piston toward one end thereof, means to admit pressure between the said one end of said cylinder and said piston for urging the latter toward the other end of said cylinder, adjustable abutments in said cylinder to halt said piston in a predetermined position in its travel toward said other end, and mechanism linked to said cylinder for normally actuating said cylinder and piston as a unit and for holding said cylinder stationary when said piston is actuated by pressure whereby said valve may be shifted independently of said mechanism and cylinder.

3. In a servomotor; a casing having a fluid inlet port, a double acting ram reciprocable in said

casing and formed with an axial bore and a radial passage in communication with the fluid inlet port of said casing and the bore of said ram; a valve member slidably carried within the bore of said ram for controlling the passage of fluid introduced within said casing by way of the fluid inlet port to and from opposite ends of said casing; a rod extending longitudinally outwardly from said valve member and having a piston at one end thereof; a cylinder surrounding said piston; spring means in said cylinder urging said piston toward one end thereof; a fluid inlet port at said one end of said cylinder for admitting fluid thereto to urge said piston toward the opposite end of said cylinder; and lever means linked to said cylinder for normally actuating said cylinder, said rod and said valve member as a unit and for holding said cylinder stationary during actuation of said piston by pressure fluid introduced within said cylinder by way of said last-named fluid inlet port, whereby said valve member may be shifted independently of said lever means.

4. In a servomotor; a reciprocable ram; a valve for selectively directing a supply of fluid to and from opposite ends of said ram; a rod extending from said valve and having a piston; a cylinder slidably receiving said piston; spring means in said cylinder urging said piston toward one end of said cylinder; a fluid inlet in said cylinder for admitting pressure fluid between the said one end of said cylinder and said piston for moving the latter toward the other end of said cylinder; adjustable abutments in said cylinder to halt said piston in a predetermined position in its travel toward said other end of said cylinder; and lever means linked to said cylinder for normally actuating said cylinder, piston and rod as a unit and for holding said cylinder stationary when said piston is actuated by pressure fluid, whereby said valve may be shifted independently of said lever means.
